(57) **CLAIM**

The ornamental design for a rope as shown and described.

DESCRIPTION

FIG. 1 is a perspective view of a first embodiment of a rope;
FIG. 2 is a front elevation view of the rope of FIG. 1;
FIG. 3 is a rear elevation view of the rope of FIG. 1;
FIG. 4 is a side elevation view of the rope of FIG. 1;
FIG. 5 is a side elevation view of the rope of FIG. 1 opposite
the side view shown in FIG. 4;

FIG. 6 is a top plan view of the rope of FIG. 1;
FIG. 7 is a bottom plan view of the rope of FIG. 1;
FIG. 8 is a perspective view of a second embodiment of a
rope;

FIG. 9 is a front elevation view of the rope of FIG. 8;
FIG. 10 is a rear elevation view of the rope of FIG. 8;
FIG. 11 is a side elevation view of the rope of FIG. 8;
FIG. 12 is a side elevation view of the rope of FIG. 8
opposite the side view shown in FIG. 11;
FIG. 13 is a top plan view of the rope of FIG. 8;
FIG. 14 is a bottom plan view of the rope of FIG. 8;
FIG. 15 is a perspective view of a third embodiment of a
rope;

FIG. 16 is a front elevation view of the rope of FIG. 15;
FIG. 17 is a rear elevation view of the rope of FIG. 15;
FIG. 18 is a side elevation view of the rope of FIG. 15;
FIG. 19 is a side elevation view of the rope of FIG. 15
opposite the side view shown in FIG. 18;
FIG. 20 is a top plan view of the rope of FIG. 15;
FIG. 21 is a bottom plan view of the rope of FIG. 15;
FIG. 22 is a perspective view of a fourth embodiment of a
rope;

FIG. 23 is a front elevation view of the rope of FIG. 22;
FIG. 24 is a rear elevation view of the rope of FIG. 22;
FIG. 25 is a side elevation view of the rope of FIG. 22;

(Continued)

FIG. 26 is a side elevation view of the rope of FIG. 22 opposite the side view shown in FIG. 25;
 FIG. 27 is a top plan view of the rope of FIG. 22;
 FIG. 28 is a bottom plan view of the rope of FIG. 22;
 FIG. 29 is a perspective view of a fifth embodiment of a rope;
 FIG. 30 is a front elevation view of the rope of FIG. 29;
 FIG. 31 is a rear elevation view of the rope of FIG. 29;
 FIG. 32 is a side elevation view of the rope of FIG. 29;
 FIG. 33 is a side elevation view of the rope of FIG. 29 opposite the side view shown in FIG. 32;
 FIG. 34 is a top plan view of the rope of FIG. 29; and,
 FIG. 35 is a bottom plan view of the rope of FIG. 29.
 The broken-line disclosure shown in the drawings illustrate portions of the rope that form no part of the claimed design. The bracketed portions shown in the FIGS. 15-28 showing a break in a portion of the rope represent an indeterminate length for that portion of the rope and form no part of the claimed design.

1 Claim, 35 Drawing Sheets
